LOCOMOTIVE STRUCTURE

Original Filed March 28, 1928

INVENTOR

INVENTOR
By Charles W. Todd

BY *S.C. Yeaton*
ATTORNEY

UNITED STATES PATENT OFFICE

CHARLES W. TODD, OF SCHENECTADY, NEW YORK

LOCOMOTIVE STRUCTURE

Original application filed March 28, 1928, Serial No. 265,388, now Patent No. 1,731,511, dated October 15, 1929. Divided and this application filed October 1, 1929. Serial No. 396,425.

This invention relates to structures for locomotives and more particularly to a novel combination of side frame members, truck center plate and pin, bumper bracket, brake cylinder brackets, crosshead guide brackets, working cylinders, distribution valve chests and/or cylinder saddles, and is a division of my copending application Serial No. 265,388, filed March 28, 1928, now Patent No. 1,731,511, of October 15, 1929. An object of the invention is to provide a structure of such type, which will be strong, rigid, and simple; which will effect a substantial economy in the cost of manufacture; which will effect a substantial reduction in the number of separately formed connected members; and which will insure accurate alignment of the side frame members, by permitting the necessary boring and slotting thereof to be performed in pairs.

Another object of the invention is to provide a crosstie member adapted to rigidly couple together a pair of side frame members, which crosstie member may be employed to support a cylinder saddle and may have incorporated with it a center pin, or a bumper bracket.

Other objects of the invention will herein-after readily appear.

The improvement claimed is hereinafter fully set forth.

In the accompanying drawings: Figure 1 is an isometric view of a fabricated structure embodying the invention the right hand side frame member being shown removed; Fig. 2, an isometric view of the removed side frame member; Fig. 3, a vertical transverse section taken on the line III—III of Fig. 1; Fig. 4, a vertical longitudinal section taken on the line IV—IV of Fig. 1; Fig. 5, a vertical, transverse section taken on the line V—V of Fig. 1; and Fig. 6, a plan view, the lower half being in section.

In the practice of the invention, referring descriptively to the specific embodiment thereof which has been selected for exemplification herein, the frame comprises two counterpart side frame members, 10, each comprising a main side frame member 11, and a front side frame member 12. Pref-

erably the main and the front side frame members are formed together as an integral casting, but it is within the contemplation of the invention to form them separately. They are also preferably, but not necessarily made of hollow or box cross-section.

Each front side frame member comprises inner and outer vertical side walls 12a and 12b; top and bottom horizontal walls, 12c and 12d, connecting the side walls; transverse walls, connecting the side walls and providing sockets, or mortises 12h and 12i, for the reception of cross tie tenons; and a vertical longitudinal flange 12j, extending above the top wall 12c, and constituting a bracket for the attachment of a brake cylinder. The side walls 12a and 12b are provided with openings in register with the sockets 12h and 12i, and the top wall 12c is provided with a transverse depression or pocket 12k adapted to receive a cylinder saddle. Suitable bolt holes 12l are provided in the side walls 12a and 12b for the reception of bolts for fastening the cylinder to the frame member.

A cross-head guide bracket 11a, is preferably, though not necessarily, formed integrally with, and projects laterally from, each main side frame member 10.

The front side frame members 12, are rigidly secured together by a truck center plate cross tie member 13, and a bumper beam bracket cross tie member 14.

The truck center plate and pin member 13, is disposed between and at the saddle pocket portion of the front side frame members, is preferably, though not necessarily, formed as an integral casting, and comprises horizontal top and bottom walls 13a and 13b; a central vertical tubular wall 13c, connecting the top and bottom walls and projecting below the bottom wall to form a center-pin 13d; vertical transverse end walls 13e, connecting the top and bottom walls vertical longitudinal side walls 13f, connecting the top, bottom, and end walls; vertical longitudinal bracing walls 13g, connecting the top, bottom, and tubular walls; vertical transverse bracing walls 13h, connecting the top, bottom, tubular walls and side walls; and

tubular tenons or dowels 13*i*, one projecting laterally from, and intermediate the length of, each side wall, the tenons being adapted to be force or press fitted into the 5 sockets 12*h*, of the front side frame members, and welded to the walls thereof. The side walls 13*f*, are provided with bolt holes 13*j* in line with holes 12*l*, for bolting the casting to the front side frame members, and 10 the top wall 13*a* is provided with openings 13*k* to permit access to certain of the bolts.

The bumper beam bracket cross tie member 14, is disposed between and at the forward end of the front side frame members; 15 is preferably though not necessarily, formed as an integral casting; and comprises, vertical longitudinal side walls 14*a*, vertical front and rear walls 14*b* and 14*c*, connecting the side walls, a horizontal wall 14*d*, connecting the side, front, and rear walls, and tubular tenons or dowels 14*e*, one projecting laterally from, and intermediate the length of, each side wall, each tenon being adapted to be force or press fitted into one 20 of the sockets 12*i*, of the front side frame members and welded to the walls thereof. The front wall 14*b* is adapted to serve as a bracket for the attachment of a bumper beam. It is within the contemplation of the invention to form the bumper beam integrally with 25 the bumper cross tie member.

Supported in the pockets 12*h* of the front side frame members, are two counterpart integral castings 16, each comprising a half 30 saddle 16*a*, a cylinder 16*b*, and a distribution valve chest 16*c*. It is within the contemplation of the invention to form the saddle, the cylinders, and the distribution valve 35 chests separately, or to combine them together, or with the front side frame members in any of the ways heretofore known.

While the bumper beam cross tie and the center pin cross tie have been shown as separately formed it is within the contemplation 40 of the invention to combine them in an integral casting.

While one of the preferred forms of construction has been shown, it is obvious that 45 many variations in procedure, form, arrangement, and construction of the parts can be made, and the invention is not therefore limited to the particular embodiment disclosed, but includes such changes and modifications 55 as come within the spirit and scope of the invention as set forth in the appended claims.

The invention claimed and desired to be secured by Letters Patent is:—

1. A cross-tie for locomotive side frames, 60 comprising a pair of elongated vertical side walls, a transverse wall connecting the side walls, and a dowel projecting laterally outward from each side wall, adapted for engagement in a complementally shaped aperture in a side frame to hold the same against both vertical and longitudinal relative movement.

2. A cross-tie for locomotive side frames, comprising a pair of elongated vertical side walls, a transverse wall connecting the side walls, and a dowel projecting laterally outward from each side wall, adapted for engagement in a complementally shaped aperture in a side frame to hold the same against both vertical and longitudinal relative movement.

3. A cross-tie for locomotive side frames, formed as an integral casting, and comprising a pair of elongated vertical side walls, a transverse wall connecting the side walls, and a dowel projecting laterally outward from each side wall, adapted for engagement in a complementally shaped aperture in a side frame to hold the same against both vertical and longitudinal relative movement.

4. A cross-tie for locomotive side frames, formed as an integral casting and comprising a pair of elongated vertical side walls, a transverse wall connecting the side walls, and a tubular tenon projecting laterally outward from each side wall, adapted for engagement in a complementally shaped aperture in a side frame to hold the same against both vertical and longitudinal relative movement.

5. A combined locomotive frame cross-tie and truck center pin, comprising a pair of elongated vertical side walls, a transverse wall connecting the side walls, a dowel projecting laterally outward from each side wall, adapted for engagement in a complementally shaped aperture in a side frame to hold the same against both vertical and longitudinal relative movement, and a center pin projecting vertically downward from the 95 transverse wall.

6. A combined locomotive frame cross-tie and truck center pin, formed as an integral casting, and comprising a pair of elongated vertical side walls, a transverse wall connecting the side walls, a dowel projecting laterally outward from each side wall adapted for engagement in a complementally shaped aperture in a side frame of a locomotive to hold the same against both vertical and longitudinal relative movement, and a center pin projecting vertically downward from the 100 transverse wall.

7. In a locomotive, the combination of a 105 pair of side frames, each formed with an aperture having a continuous wall and disposed between its upper and lower faces; a cross-tie comprising elongated vertical side walls abutting the side frames, a transverse wall connecting the side walls, and a dowel projecting laterally outward from each side wall and fitted in one of the apertures to hold the side wall against both vertical and longitudinal relative movement; and a cylinder 110

inder saddle formed separately from, and superposed over the cross-tie.

8. In a locomotive, the combination of a pair of side frames, each formed with an aperture having a continuous wall and disposed between its upper and lower faces; a cross-tie comprising elongated vertical side walls abutting the side frames, a transverse wall connecting the side walls, and a tubular tenon projecting laterally outward from each side wall and fitted in one of the apertures to hold the side frames against both vertical and longitudinal relative movement; and a cylinder saddle formed separately from and superposed over the cross-tie.

9. In a locomotive, the combination of a pair of side frames, each formed with an aperture having a continuous wall and disposed between its upper and lower faces; a member comprising elongated vertical side walls abutting the side frames, a transverse wall connecting the side walls, a dowel projecting laterally outward from each side wall and fitted into an aperture of one of the side frames to hold the same against both vertical and longitudinal relative movement, a center pin projecting vertically downward from the transverse wall; and a cylinder saddle formed separately from and superposed over the said member.

10. In a locomotive, the combination of a pair of side frames, each formed with an aperture having a continuous wall and disposed between its upper and lower faces; a cross-tie formed as an integral casting, comprising elongated vertical side walls abutting the side frames, a transverse wall connecting the side walls, and a dowel projecting laterally outward from each side wall and fitted in one of the apertures to hold the side wall against both vertical and longitudinal relative movement; and a cylinder saddle formed separately from and superposed over the cross-tie.

11. In a locomotive, the combination of a pair of side frames, each formed with an aperture having a continuous wall and disposed between its upper and lower faces; a cross-tie formed as an integral casting, comprising elongated vertical side walls abutting the side frames, a transverse wall connecting the side walls, and a tubular tenon projecting laterally outward from each side wall and fitted in one of the apertures to hold the side frames against both vertical and longitudinal relative movement; and a cylinder saddle formed separately from and superposed over the cross-tie.

12. In a locomotive, the combination of a pair of side frames, each formed with an aperture having a continuous wall and disposed between its upper and lower faces; a member formed as an integral casting, comprising elongated vertical side walls abutting the side frames, a transvers

connecting the side walls, a dowel projecting laterally outward from each side wall and fitted in one of the apertures to hold the side wall against both vertical and longitudinal relative movement, and a center pin projecting vertically downward from the transverse wall; and a cylinder saddle formed separately from and superposed over the member.

13. In a locomotive, the combination of a pair of side frames, each formed with an aperture having a continuous wall and disposed between its upper and lower faces; a cross-tie comprising elongated vertical side walls abutting the side frames, a transverse wall connecting the side walls, and a tubular tenon projecting laterally outward from each side wall and force fitted in one of the apertures to hold the side frames against both vertical and longitudinal relative movement; and a cylinder saddle formed separately from and superposed over the cross-tie.

14. In a locomotive, the combination of a pair of side frames each formed with an aperture having a continuous wall and disposed between its upper and lower faces; a cross-tie comprising elongated vertical side walls abutting the side frames, a transverse wall connecting the side walls, and a tubular tenon projecting laterally outward from each side wall, fitted in one of the apertures to hold the side frames against both vertical and longitudinal relative movement, and welded to the wall thereof; and a cylinder saddle formed separately from and superposed over the cross-tie.

15. In a locomotive, the combination of a pair of side frames, each formed with an aperture having a continuous wall disposed between the upper and lower faces of the side frame; a member comprising elongated vertical side walls abutting the side frames, a transverse wall connecting the side walls, a tubular tenon projecting laterally outward from each side wall and fitted in one of the apertures and welded to the walls thereof to hold the same against both vertical and longitudinal relative movement, and a center-pin projecting vertically downward from the transverse wall; and a cylinder saddle formed separately from and superposed over the member.

16. In a locomotive, the combination of a pair of front side frame members, of box shape cross-section, each formed with an aperture having a continuous wall disposed between the upper and lower faces of the frame members; a cylinder saddle supported on the frame members; and an elongated cross-tie disposed beneath the saddle and comprising elongated side walls having dowels fitted each in an aperture to hold the side frame members against both vertical and longitudinal relative movement.

17. In a locomotive, the combination of a

pair of front side frame members, of box shape cross-section, each formed with an aperture having a continuous wall disposed between the upper and lower faces of the side frame member; a cylinder saddle supported on the frame members; and an elongated member comprising a cross-tie having elongated walls, and a center pin formed thereon and projecting vertically downward, and dowels on said walls fitted in the apertures of the frame members to hold the same against both vertical and longitudinal relative movement.

18. In a locomotive, the combination of a pair of front side frame members of box shape cross section each formed with an aperture having a continuous wall disposed between the upper and lower faces of the side frame; a pair of members supported on the frame members, each comprising a portion of a cylinder saddle, a cylinder and a valve chest; and an elongated member disposed beneath said saddle portions and comprising a cross-tie having elongated side walls, and a center pin formed thereon projecting vertically downward and dowels on said walls fitted in the apertures of the frame members to hold the same against both vertical and longitudinal relative movement.
